UNITED STATES PATENT OFFICE.

LEOPOLD LICHTENFELD, OF VIENNA, AUSTRIA.

PARQUET FLOORING.

Application filed May 26, 1923, Serial No. 641,690, and in Austria June 1, 1922.

The ordinary parquetry pieces (variously known as plates, slabs, squares, strips, etc., according to their shape and thickness) that make up a parquetry floor, have been 5 manufactured hitherto by gluing the parquetry veneers (of a thickness of from 7 to 10 millimetres) upon a tongued and grooved under-plate composed of a frame about 25 to 35 mm. thick, filled in with 10 grooved panels so that the ordinary parquetry piece has a thickness varying from 35 to 40 mm. These parquetry pieces are fixed on to the under-floor by means of nails driven through the lower side of the groove 15 of the parquetry piece obliquely into the under-floor.

The present invention has for its object to provide an improved parquetry piece (hereinafter called "parquetry plate") and 20 an improved method of fixing such parquetry plate upon the under-floor.

The improved parquetry plate according to this invention is manufactured as follows:

25 The parquetry veneers are assembled together so as to constitute the parquetry design, on a support or grid composed of parallel battens upon which the veneer sections are glued closely together in such a 30 manner that portions of the grid-battens project on all four sides beyond the assembled veneering or sections of veneering.

A parquetry plate thus formed, is fixed 35 in place by being laid upon the under-floor in such a manner that the grid-battens cross the boards of the under-floor, and then the projecting portions of the grid-battens are nailed to the under-floor.

The several parquetry plates being laid 40 so that the adjacent ends of their grid-battens abut against one another intersection "channels" are thus formed between the veneer sections of the plates, and these channels are filled-in with parquetry strips which 45 are mitred at 90° where the ends of four such strips meet at one point. These parquetry strips cover up the joints between the projecting portions of the grid-battens and thus give the appearance of ordinary parquetry flooring. The parquetry strips are 50 fixed by gluing upon the meeting ends of the grid-battens.

One embodiment of this invention is illustrated by way of example in the accompanying drawings in which—

55 Figures 1 to 3 show an improved par-

quetry floor in various stages of construction. Figure 1 being a plan, and Figures 2 and 3 being sections taken along the lines A—A and B—B respectively of Figure 2. 60

Figure 4 is a perspective view of an improved parquetry plate as shown separately.

The parquetry plates are composed each of a grid built of parallel battens *m* on which sections *n* of veneering of a thickness 65 of 5 to 7 millimetres are fixed by means of waterproof glue. Portions of the grid battens *m* project beyond all of the edges of the sections *n* to an extent equal to about one-half the width of the parquetry strips 70 that are to be laid between the several parquetry plates. The laying of the several parquetry plates upon an under-floor *a* is effected by laying them close together so that their grid-battens *m* with their ends 75 touching one another, cross the boards *a* of the under-floor at an angle of 45°. The portions of the grid-battens *m* projecting from all four sides of the sections *n* of each parquetry plate are then nailed to the under-floor *a*, so that each parquetry plate *(n, m)* is fixed to the under-floor *a* by means of a comparatively large number of nails. 80

The mutually intersecting "channels" *O* formed between the veneer sections *n* after 85 the parquetry plates have been nailed down, are then filled-up by the insertion of parquetry strips *h* having the same thickness as the sections *n* of the parquetry plates. These strips *h* are mitred at 90° at their 90 ends so that every four meeting strips constitute a complete cross.

The strips *h* are fixed by gluing with waterproof glue on the projecting portions 95 of the grid-battens.

The advantages of this improved parquetry lie in the saving in material and labour, in the complete prevention of warping, and in the entire absence of joints.

The saving in wood is due to the fact that 100 in ordinary parquetry the frame alone must have a thickness of 30 mm. in order to give sufficient thickness to the sides of the tongue-grooves.

The saving in labor is due to the fact that 105 the ordinary parquetry piece comprises a grooved frame with panelling let into the latter, whereas the support of the improved parquetry plate consists merely of a plurality of grid-battens which can be brought into 110 their correct position very easily by means of templates or jigs, and the veneer sections

may be glued upon these grid-battens whilst the latter are in the said position.

The advantages afforded by the improved parquetry flooring in respect of their mode of fixing and of the absence of joints, are due to the fact that in the ordinary parquetry flooring the several parquetry pieces had to be fixed by means of nails driven obliquely into the grooves, and this work had to be done very carefully in order to avoid breaking off the lower sides of the tongue-grooves, and consequently it was advisable to restrict the number of the nails to be driven.

Now, in contradistinction to that usual, but really irrational, method of fixing, the fixing of the improved parquetry plates is done by nailing the ends of the grid-battens directly on to the under-floor, so that the fixing adopted in carrying this invention into effect is very strong and technically correct.

This very strong fixing of the parquetry plates is further increased by the feature that the butting ends of the grid-battens are fastened together by the parquetry strips which are glued upon them and which cover the joints between the said grid-batten ends, so that entire parquetry flooring is composed of parts glued together.

Since the parquetry strips are glued upon the grid-batten ends, no interstices remain between the edges of the sections of adjacent parquetry plates and the parquetry strips, so that the improved parquetry flooring is entirely free from the interstices which it is almost impossible to prevent from occurring between the parquetry pieces of the ordinary parquetry flooring notwithstanding the greatest care exercised in laying such ordinary flooring.

A further advantage of the improved parquetry flooring consists in the fact that the crossed arrangement of the grid-battens relatively to the boards of the under-floor has the result of almost wholly preventing the wood from warping.

The improved parquetry plates as hereinbefore described and shown separately in Figure 4, can be used with equally great advantage for the construction of ceilings and wainscot. In both those cases, it is quite sufficient to fix to the ceiling or to the wall, a framing of boards or slats to serve as a support (analogous to the under-floor hereinbefore mentioned) for the several parquetry plates. In these cases also the gluing of the parquetry strips upon the projecting grid-batten ends will provide a parquetry having no interstices.

The improved parquetry is also applicable in the manufacture of doors and furniture.

Having now particularly described and ascertained the nature of my said invention and in what manner the same is to be performed, I declare that what I claim is:

1. A parquetry plate comprising a grid-like support composed of a plurality of battens arranged in spaced parallel relation, and sections of veneering secured upon the battens in such manner that portions of all of the battens project beyond all of the edges of the section of veneering.

2. A parquetry flooring comprising a foundation of suitably spaced parallel slats, a plurality of parquetry plates arranged in rows diagonally of the slats and each composed of a plurality of battens forming a grid-like support, a section of veneering glued to the battens so that portions of the ends and sides of the battens project beyond all of the sections of veneering leaving intersecting channels between the adjacent sections of veneering in the several plates, and strips of veneering secured in said channels so as to abut adjacent strips as well as the edges of the sections of veneering and having the upper surfaces flush with the sections of veneering, and the battens of each plate being arranged to cross the slats of the foundation.

In testimony whereof I affix my signature.

LEOPOLD LICHTENFELD.
